UNITED STATES PATENT OFFICE.

WILLIAM TINSLEY, OF NEW YORK, N. Y.

IMPROVEMENT IN COOKING-STOVES.

Specification forming part of Letters Patent No. 43,243, dated July 21, 1864.

To all whom it may concern:

Be it known that I, WILLIAM TINSLEY, of the city, county, and State of New York, have invented a new and Improved Cooking-Stove; and I do hereby declare that the following is a full, true, and exact description of the construction and operation of the same, reference being had to the annexed drawings, making part of this specification, in which—

Figure 1 is a general ground plan. Fig. 2 is ground plan of the middle plate, *b*. Fig. 3 is a perspective of the air-passage *X* with its register and valve. Fig. 4 is a general perspective of the whole.

Plate a.—My stove has three visible horizontal plates, *a*, *b*, and *c*. The bottom plate, *a*, has a pair of ash-pits, over which, upon a plinth-box *c* containing the grate and sifting apparatus, is built a pair of cylindrical fire-pots, *o o*, Fig. 1. Behind them is the oven.

Plate c.—The top plate, *c*, is of the ordinary form, made for four boilers.

Plate b.—The middle plate, *b*, is parallel to *c*, about three inches distant, and forms the top of the oven. It has two circular openings in front to receive the tops of the fire-pots; also another perforation or opening, *X*, Fig. 2, (about an inch back of the fire-pots,) in the form of an irregular triangle. Two of its sides, *s s*, are arcs of circles concentric with the fire-pots. The other side, *r*, is a right line drawn from above the crown of each arc. There are also two slits, *e e*, at the back end in the range of the side flues. The flues are the common long draft.

Curves.—Behind the fire-pots are built two curved plates, *s s*, Fig. 1, from plates *a* to *b*. Said plates are parallel to and partially inclose the fire-pots, each arc containing about one hundred and sixty-five degrees. Those curved plates bear upon a flange, the bottom of the oven, and make its front.

Passage X.—The triangle *X*, Figs. 1 and 2, is a hot air passage opening above into the chamber between plates *b* and *c*, and below into the under flues. The passage is closed above by a sliding cover lying on plate *b* and turning on a center near the oven sides or jambs. It is closed below by a valve, *p*, beneath the oven, Fig. 3, and operated by its journal passing through the jamb.

Ventilator.—Within the passage *X* is a perforation, *V*, Fig. 1, through plate *a*, which is

opened or closed by a valve, which valve is operated by its journal passing through the jamb.

Register.—Plate *r* of the triangle is pierced in slits, which are covered by a similar sliding register, Fig. 3.

Dampers.—There are two sliding dampers, *W W*, Fig. 1, lying upon plate *b*, having slits *ff*, which correspond to slits *e e* when half drawn out. Their use is to cover the side flues. The half-draw is felt by a notch in the rod.

Operation: I here describe the peculiar operation and functions of the air-passage *X* and its assisting apparatus. When the passage is closed, the fire and heated air pass over the oven, (subject to the ordinary damper,) as is common. When the passage is opened and the slides *W W* drawn out, the fire and hot air pass down the triangle in front and under the middle of the oven, out by the chimney. Thus we command three-fourths of the oven-front with one fire, which is sufficient for bread or light baking, which cannot be well done without the passage *X*. When both fire-pots are used for washing or ironing, the heat upon the oven is too great for baking bread, pies, cakes, &c., when the full power is thrown in, but by closing the register and opening the valve *V* the oven may be moderated to a proper temperature, and again elevated for baking meat, by the directly-opposite arrangement. When it is desired to cool, ventilate, or purify the oven, the valve *V* and register are opened, and slides *W W* are drawn half-way out. The cold air then enters from below and passes through the oven, carrying away by the smoke-pipe all unpleasant steam, burning or scorching smells, and vapors.

By using the air-passage *X* we can heat the oven from the bottom, and avoid the fault of nearly all stoves—that is, of scorching the upper side of all viands while baking. There is no danger of meat being scorched below while protected by its own gravy, or of bread or pastry while protected by a raised pan. Thus we have an under draft, an upper draft, the common return draft, and a ventilating apparatus. The draft is also divided and the heat generated within the passage *X* passes under the oven.

The ventilator acts as a blower by admitting a current of cold air through the upper

cover, which draws the fire after it toward the smoke-pipe.

I make no pretension to the simple idea of a fire or air passage in front of the oven, or to a ventilator, as a novelty; but

I claim—

That particular fire or air passage with its apparatus, the slitted plate *r* and its register, (forming with the curved plates *s s* the

triangle,) the upper cover, the under valve, *p*, the ventilator, and the back slides, *W W*, constructed and operated as set forth, the whole being considered a combination.

WILLIAM TINSLEY.
